UNITED STATES PATENT OFFICE.

JOHN B. RUSS, OF SHELTON, CONNECTICUT, ASSIGNOR TO THE BASSETT METAL GOODS COMPANY, INC., OF DERBY, CONNECTICUT, A CORPORATION OF CONNECTICUT.

DESIGN FOR A LOCK OR SIMILAR ARTICLE.

Application filed December 14, 1927. Serial No. 24,475. Term of patent 7 years.

To all whom it may concern:

Be it known that I, JOHN B. RUSS, a citizen of the United States, residing at Shelton, county of Fairfield, State of Connecticut, have invented a new, original, and ornamental Design for a Lock or Similar Article, of which the following is a specification, reference being had to the accompanying drawing, forming a part thereof.

The drawing shows a perspective view of a lock showing my new design.

I claim:

The ornamental design for a lock or similar article as shown.

JOHN B. RUSS.
